(74) Attorney, Agent, or Firm—Ostrager Chong Flaherty & Broitman P.C.

(62) Division of application No. 29/193,478, filed on Nov. 10, 2003.

CLAIM

(51) **LOC (8) Cl. 13-03**

The ornamental design for an electrical dimmer switch and cover plate, as shown and described.

(52) **U.S. Cl. D13/170; D13/169**

DESCRIPTION

(58) **Field of Classification Search** ..... D13/169, D13/170, 174, 177; D8/350-353; 174/48, 174/52.1, 66, 55; 200/5 A, 5 R, 16 R, 42,01, 200/237, 241, 293, 296, 297, 308, 319, 313-314, 200/324, 329, 331, 341, 519, 547, 531, 536, 200/541, 550, 571; 315/129, 136, 291, 307, 315/312, 362; 361/622, 643

FIG. 1 is a front, bottom and right side perspective view of the design.

See application file for complete search history.

FIG. 2 is a front view thereof.

(56) **References Cited**

FIG. 3 is a right side view thereof.

FIG. 4 is a left side view thereof.

U.S. PATENT DOCUMENTS

FIG. 5 is a top plan view thereof; and,

FIG. 6 is a bottom plan view thereof.

The back forms no part of the design.
